UNITED STATES PATENT OFFICE

2,462,972

SLACK CONTROLLING DEVICE FOR CABLES

Thomas M. Johnson, Baltimore, Md.

Application November 5, 1946, Serial No. 707,965

1 Claim. (Cl. 254—175)

1

This invention relates to new and useful improvements and structural refinements in slack controlling devices for cables, and the principal object of the invention is to provide a device of the character herein described, such as may be conveniently and effectively employed in association with winches on cranes, steam shovels, hoists, and on other types of raising or lowering equipment.

A further object of the invention is to provide a slack controlling device which is automatically actuated by the tension of the cable with which it is employed.

Another object of the invention is to provide a slack controlling device whereby the rotation of the winch, or the like, will be resisted when the slackness of the cable reaches a predetermined degree.

A still further object of the invention is to provide a slack controlling device which is simple in construction and operation, dependable in use, and which will not easily become damaged.

With the above more important objects in view, and such other objects as may become apparent as this specification proceeds, the invention consists essentially of the arrangement and construction of parts as illustrated in the accompanying drawings, in which:

Figure 1 is a side elevation of the invention, showing the same in readiness for use.

Figure 2 is an end view, taken substantially in the direction of the arrow 2 in Figure 1.

Figure 3 is a cross sectional view, taken substantially in the plane of the line 3—3 in Figure 1, and

Figure 4 is a cross sectional view, taken substantially in the plane of the line 4—4 in Figure 3.

Like characters of reference are used to designate like parts in the specification and throughout the several views.

Referring now to the accompanying drawings in detail, the invention consists of a slack controlling device designated generally by the reference character 10, the same being associated with a winding winch 11, such as may include one or more of the winding drums 12. For purposes of illustration, two winding drums are shown in the accompanying drawings, each being provided with the slack controlling device hereinafter more fully described. The structure of the two slack controlling devices is substantially the same, and accordingly, a description of one will suffice for both.

Each of the winding drums 12 is, of course,

2

adapted to receive a cable 13, and the drum is equipped with a suitable brake, as exemplified in the drawings by the external contracting band brake 14. One end of the band 14 is attached to the framework 15 on which the winch is mounted, the remaining end of the band being connected by a suitable rod 16 to a crank 17, the latter in turn, being secured upon a shaft 18.

This shaft is rotatably journaled in suitable bearings 19 provided in the framework 15 and a lever 20 is also secured to the shaft, as will be clearly apparent from the accompanying drawings.

The lever 20 is, in turn, connected to a suitable control rod 21, the latter being intended for manual manipulation, whereby the brake may be applied or released as desired.

The essence of the invention resides in the provision of a bell crank 22, the same being pivotally connected as at 23 to the framework 15. The arms of the crank 22 are of unequal lengths, the relatively long arm 24 carrying at its outer end a roller 25 rotatably mounted on a suitable pin or shaft 26.

It will be noted that the roller 25 rides upon, so to speak, the cable 13, as is best shown in Figure 1.

The relatively short arm 27 of the crank 22 is provided with a pin 28, the latter in turn, engaging a slot 29 formed in one end of a link 30. To facilitate longitudinal adjustment, this link is, in effect, composed of two sections connected together by a turnbuckle 31, and the remaining end of the link 30 is pivotally connected as at 32 to the aforementioned lever 20.

It will be also noted that the lever 20 is provided with a pin 33, this being slidably engageable with a slot 34 formed in the end of the aforementioned control rod 21.

When the invention is placed in use, the roller 25 will ride upon the cable 13 as has been already explained. When slackness occurs in the cable, the roller 25 and the associated arm 24 will fall downwardly in the direction of the arrow 35,

thereby moving the link 30 as at 36 and tightening the brake band 14 so as to resist the rotation of the associated drum 12. The advantageous nature of the invention is thus clearly apparent and the advantages may be particularly appreciated when the winch is employed for hoisting or lowering a load which is hidden from the view of the operator.

The brake band 14 may be actuated manually when so desired by means of the control rod 21. In such event, the link 30 will, of course, move in

the direction of the arrow 36, but it will be noted that this motion will not be transmitted to the bell crank 22, since the pin 28 will simply slide in the slot 29. Conversely, when the brake band 14 is actuated by the slack controlling device, the pin 33 will slide in the slot 34 and no motion will be transmitted to the control rod 21. It will be apparent that in this manner, the two brake actuating devices are capable of independent operation without interference.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to which do not depart from the spirit and scope of the invention as claimed.

What I claim as my invention is:

In association with a cable winding winch equipped with a band brake and with a manually operated control rod for actuating said brake, a

slack controlling device comprising in combination, a bell crank pivoted to the framework of said winch, a roller rotatably mounted on one arm of said crank and adapted to ride upon said cable, a lever pivoted to said framework and operatively connected to said brake, a pin provided on said lever, said rod being slotted to slidably receive said pin, a further pin on the remaining arm of said crank, and a connecting link pivoted at one end thereof to said lever, the remaining end of said link being slotted to slidably receive said last mentioned pin, said bell crank, link and lever responding to slack in said cable and actuating said brake independently of said rod.
